UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,329,535.

Specification of Letters Patent.

Patented Feb. 3, 1920.

Application filed April 9, 1919. Serial No. 288,813.

To all whom it may concern:

Be it known that I, WILLIAM L. MCGRATH, a citizen of the United States, residing at Elmira, Chemung county, New York, have 5 invented certain new and useful Improvements in Engine-Starters, of which the following is a specification.

My invention relates to a starter for the starting of an engine such as an internal 19 combustion engine and pertains more particularly to means for facilitating and assuring the proper register and meshing of the teeth of the driving member or pinion with the engine member such as the fly 25 wheel. My invention is therefore concerned with the structure of the meshing ends of the teeth of the pinion of the drive or transmission of the starter.

My invention is herein shown embodied 20 in a drive or transmission of the well known Eclipse-Bendix type which is characterized by a rotatable member such as a screw shaft, generally operated by a starting motor, and a pinion screw-threaded thereon and adapted 25 to be automatically advanced longitudinally into mesh with the fly wheel or other engine member and to be automatically demeshed therefrom after the engine has started on its own power. My invention has reference 30 to the formation of the ends of the pinion teeth which first reach the fly wheel and which at times, in the advance movement of the pinion, are not always presented in register with the teeth of the fly wheel but are 35 liable to abut thereagainst end to end. The peculiar formation of this end of the pinion teeth is for the purpose of facilitating the meshing and registering of the teeth and reducing the possibility of abutting end to end 40 to a minimum or practical nullity. My invention is applicable to the engaging pinion whether it be directly screw-threaded on the screw shaft or be indirectly controlled and operated by such shaft through the 45 medium of some control member directly acted upon by the screw shaft.

In the drawings Figure 1 is an elevation of a starter embodying my invention; Fig. 2 an enlarged section on the line 2-2 of 50 Fig. 1; Figs. 3, 4 and 5 perspectives of one end of the pinion teeth taken from different angles; Fig. 6 a detail view illustrating the meshing operation; and Fig. 7 a detail view 55 of a portion of a fly wheel.

For the purpose of a clear and definite

description I will describe my invention in connection with a drive or transmission of the standard Eclipse-Bendix type such as exemplified in patents heretofore issued to Vincent Bendix such as Patents No. 60 1,125,935, dated January 26, 1915, and No. 1,172,864, dated February 22, 1916. It will therefore suffice to specify the parts in general by reference characters as follows:

The driving shaft 1, which is here shown 65 as the extended armature shaft of a starting motor indicated at A and therefore direct-driven, although it may be indirect-driven if desired, is operatively connected through the driving collar 2, pin 3 and coiled driving spring 4 with the driving head 5 of the screw shaft 6. On this shaft there is screw-threaded, in the present instance, the driving member or pinion 7 which is adapted 70 to be advanced longitudinally on the screw shaft into mesh with the teeth 8^a of the engine member which is here the fly wheel 8.

The ends of the pinion teeth adjacent the fly wheel teeth, that is the ends which first come into mesh therewith, have the special 80 and novel formation illustrated in the drawing. As shown, the outer corner of each tooth is cut back at 7^a leaving a curved portion thereat beginning part way up from the base level of the tooth at 7^b and continuing back and thence upwardly where it emerges at 7^c at the top line or plane of the tooth which latter point is a comparatively 85 considerable distance from the front edge of the tooth.

In addition each tooth at this end is cut 90 away at 7^d, such cut being at an angle to the longitudinal or horizontal axis of the tooth and beginning at the front end of such tooth near the base thereof at 7^e and extending 95 backwardly but at an angle and terminating at 7^f. This latter cut is on one side only of each tooth, the other side 7^g of the tooth, which is the driving side, remaining straight.

By virtue of this peculiar construction or formation of the teeth the space between the ends of the teeth of the pinion as presented to the fly wheel teeth is formed to a maximum, there being at the tooth base 105 only a small portion indicated at 7^h. The dotted measurement line *a* in Fig. 7 denotes the width of the tooth-engaging space near the top of the fly wheel teeth and obviously that space is a maximum so that the chances 110

of proper meshing are enormously increased and the chances of abutting end to end are reduced to a minimum.

It is obvious that when the pinion teeth are presented to the fly wheel teeth somewhat out of register, the latter teeth will strike against the inclined surface 7^a whereupon the pinion will be moved slightly so as to cause proper register.

Moreover by having the cutaway portion 7^a , the pinion teeth will be permitted to enter the fly wheel teeth without any contact between such fly wheel teeth and the broad face 7^a of the pinion tooth, permitting the lower portion of each tooth, that is said portion 7^a , to first contact the fly wheel teeth and be guided or moved into proper register.

The described construction of the pinion teeth is such as to permit of the ready meshing thereof with the fly wheel teeth whether chamfered or not and whether rounded as shown in Figs. 1 and 6 or not.

I claim:

1. For use in an engine starter transmission or drive, a pinion having the engaging end of each of its teeth cut away substantially vertically at an angle to its longitudinal axis, such end being curved from a point slightly above the base of the tooth and extending backwardly into the tooth and thence upwardly to the top edge of the tooth.

2. For use in an engine starter transmission or drive, a pinion having teeth of usual or appropriate cross section and having the engaging end of each tooth substantially rectangular in shape and extending only a short distance above the base thereof, such end being chamfered backwardly at an angle to the longitudinal axis of the tooth and also curved from the top of such rectangular end to the top edge of the tooth at a distance back from such engaging end of the tooth.

WILLIAM L. McGRATH.
